MOTOR

Oliver H. Simmons, Chicago, Ill., assignor to
 Buell Manufacturing Co., Chicago, Ill., a corporation of Illinois

Application April 5, 1940, Serial No. 328,007

13 Claims. (Cl. 121—150)

This invention relates to a single acting fluid pressure motor having a pressure operated valve for controlling the admission and exhaust of motive fluid to and from the motor cylinder. The invention is of special utility for a rocker jack motor, namely an upright motor whose piston carries a jack which with the load thereon is reciprocated vertically by operation of the motor. Such a device may be used under an automobile or motor vehicle for rocking or vibrating the vehicle body or chassis relative to its supporting springs during greasing, as is desirable to promote effectual penetration of grease between the spring leaves and into the shackles and spring joints.

Objects of the invention are to provide an improved motor for use as a rocker jack motor or under conditions in which the motor piston is moved reversely by a load or by reaction of a force opposing the working stroke of the piston; to provide a single acting fluid pressure motor with a pressure operated valve which will control the motor efficiently and in a manner advantageous for the purposes of a rocker jack motor, as hereinafter indicated; and to provide such a motor with a pressure operated valve of practicable, efficient and reliable character.

The invention further pertains in part to certain novel features in reference to the piston and piston rod assembly and the lubrication of the cylinder and piston rod.

An illustrative embodiment of the invention in a rocker jack motor of one practicable construction is shown for example in the accompanying drawings. The invention will be described with reference to the drawings and will be more particularly pointed out and defined in the claims appended hereto.

In said drawings:

Fig. 1 is a central vertical section of the illustrative rocker jack motor, showing the valve therefor in position for admitting motive fluid to the working end of the motor cylinder.

Fig. 2 is a partial sectional view on a larger scale showing the valve in position to allow exhaust from the working end of the motor cylinder.

Fig. 3 is a plan view of a valve operating piston.

Fig. 4 is a side elevation partly in section of the motor valve body and connections therewith.

Fig. 5 is a detail view of a part of a connection with a lateral cylinder port.

Fig. 6 is a view similar to Fig. 5 showing a check valve in said connection.

In the drawings, 1 is the base plate of a rocker

jack motor comprising the upright cylinder 2 and the jack-carrying piston 3 working therein. In the specific construction shown, the piston is affixed to the lower end of a tubular piston rod 4 in which telescopes a jack section 5 shown as a ratchet bar engageable by holding dogs 6 pivoted to ears 7 of the collar 8 affixed to the upper end of the piston rod. The jack section 5, which may be lifted to obtain a quick rough adjustment of the jack, is interiorly screw-threaded and engaged by the jack screw 9 having the jack head 10 fixed thereto. The jack construction shown is but one example of a suitable jack to be carried by the motor piston. At 11 there is diagrammatically represented a load sustained by the jack, which may be considered to represent so much of the weight of an automobile body as the jack takes from the vehicle springs.

A guide for the piston rod may be provided by the sleeve 12 affixed to the upper end of the cylinder. The piston rod has a loose sliding fit in the guide sleeve, allowing venting of the cylinder space above the piston. Additional venting capacity may be provided by a groove 13 in the guide sleeve. A desirable construction is shown for connecting the motor piston to the tubular piston rod. As shown, the piston is formed with a circular recess in which the lower end of the tubular piston rod is fitted, and the parts are secured in assembly by a bolt 16 connecting the piston to a thick washer or plug 14 fitted in the piston rod and butting against a spring locking ring 15 engaging an annular groove in the piston rod, thereby clamping the piston rod to the piston. The same bolt 16 is utilized to hold the bottom piston plate 17 to the piston head. A rubber packing ring 18 is shown clamped between the piston head and bottom piston plate. To the upper side of the piston is secured an oil saturated felt ring 19 for lubricating the cylinder walls. An oil filling opening may be provided by a fitting 20 in the upper end of the cylinder, said opening being normally closed by its removable screw cap.

Reference will now be made to the pressure operated valve for controlling admission and exhaust of motive fluid to and from the lower end of the motor cylinder. In the drawings, the numeral 21 designates a valve body, shown formed as one piece except for the attached cap 22. For convenience the valve body is shown attached to the motor base plate 1, though it is not necessary that it be mounted directly on the motor, as the valve could be in either immediate or distant association with the motor. The

valve body contains a motive fluid inlet chamber 23 (Fig. 4) into which motive fluid from a source of supply is introduced through any suitable connections including a manually operated cut off and throttling valve 24 (Fig. 4) and filter 25. Compressed air, being conveniently available at automobile servicing stations, is preferably utilized as the motive fluid. The pipe 26 shown in Fig. 4 may be assumed, for example, to be connected by a rubber hose with a source of compressed air for operating the motor. The valve 24 in Fig. 4 is normally closed, and opened when it is desired to operate the motor.

Flow of motive fluid to and from the working end of the motor cylinder is controlled by a movable valve member 27 shown as a small piston valve which slides in a small bore chamber 28 communicating by the inlet port 29 with the motive fluid inlet chamber 23. The valve chamber 28 communicates by a lateral port 30 with the so-called cylinder passage 31 in the valve body, namely a passage in communication with the working end of the motor cylinder. In the specific construction shown the passage 31 communicates with the lower end of the motor cylinder through the duct 32 in the motor base plate 1. By a lateral port 33, the valve chamber communicates with an exhaust passage 34. The valve 27 works between the inlet and exhaust ports 29 and 33 and in its reciprocations passes the so-called cylinder port 30. The valve 27 is always exposed during motor operation to pressure of motive fluid from the inlet chamber 23, communicating with the valve chamber by the inlet port 29, and the valve is operated by such pressure to the position shown in Fig. 1, thereby admitting motive fluid to the cylinder through the passage 31 and cutting off communication between the cylinder and exhaust passage 34. By intermittent application of fluid pressure to a piston 35, motion of which is transmitted to the valve member 27 by the valve rod 37, the valve is reversely operated to the position shown in Fig. 2, cutting off admission and establishing connection between the cylinder passage 31 and exhaust passage 34. The pressure area of the piston 35 is many times larger than that of the small piston valve 27 exposed to the pressure of the motive fluid to be admitted. The piston 35, shown having a piston ring 36, works in a chamber 38 in communication with the exhaust passage 34 through the passages 39 and 40. During exhaust a pressure of exhausting fluid is maintained on the piston 35, and the valve will be held in position for exhaust so long as the force on the piston 35 exceeds that on the small piston 27.

To prevent building up a back pressure under the piston 35, the space 41 under the piston communicates with the atmosphere through the outlet port 42. The valve body 21 may be formed with a boss 43 limiting the motion of the piston 35 in the direction for actuating the valve to exhaust position. The space around said boss 43 is preferably filled with a porous packing 44 of wool, felt or other suitable air-filtering material. The chamber 38 in which the piston works is suitably vented; provision for venting being made in this instance by the gap 45 in the piston ring. The piston preferably comprises a pair of spaced discs holding between them the expandable piston ring 36 in contact with the cylinder walls of the chamber 38. The piston ring 36 may be of Bakelite or the like. Discharge of fluid from the chamber 38 through the gap

45 in the piston ring and through the air-filtering medium 44 is sufficiently restricted to insure backing up of exhaust pressure in the exhaust passages 34, 39, 40 during exhaust. In the specific construction shown, the piston 35 is fixed to the upper end of the valve rod 37 which slides in a bore in the valve body, said valve rod being reduced in diameter at 46 to allow flow of exhausting fluid around the valve rod, thereby providing the piston head 27 working in the chamber 28 which is a continuation of the bore in which the upper part of the valve rod is guided.

A pipe or tube 47 is shown connected with the valve body by the screw plug 48. The passage 15 through said pipe and screw plug communicates at 49 with the exhaust passage 34 and with the passage 39 leading to the piston chamber 38. The passage in said pipe 47 is connected with the motor cylinder through a lateral port 50 so located that the motor piston will pass said port in its working or up stroke; whereupon motive fluid discharging from the working chamber of the motor cylinder into the passage in pipe 47 will cause a quick pressure impulse or puff in 20 the piston chamber 38 for operating the motor valve reversely to the exhaust position shown in Fig. 2. As shown in Fig. 2, the motor piston in its up stroke has just passed the port 50, with the result that the motor valve has been operated 25 to the exhaust position shown, and the cylinder now commences to exhaust from its lower end. As the motor piston descends, it covers the port 50, and while said port is covered the exhaust from the lower end of the motor cylinder takes 30 place through the piston chamber 38. As the descending piston passes below the port 50, the exhaust can take place partially through the piston chamber 38 and partially through the port 50 into the cylinder space above the piston. Provision is made for suitably restricting the exhaust through the pipe 47 and port 50, as for 35 example by forming the port 50 so small in relation to the exhaust passages in the valve body as to insure backing up of pressure in said passages during exhaust. As shown in Fig. 5, the lateral cylinder port 50 is connected with the pipe 47 through a fitting 51 the passage in which may be restricted or cut off by a suitably manually operated valve 52, preferably of the 40 needle valve type.

The operation of the motor as thus far described will be briefly summarized as follows: Assuming that the valve 24 (Fig. 4) in the motive fluid supply line is opened when the motor piston 55 is at the bottom of its stroke, the pressure operated motor controlling valve is immediately actuated to the position shown in Fig. 1 for admitting motive fluid to the lower end of the cylinder, such actuation being by pressure of the motive fluid from the source of supply on the small valve piston 27. In its working or up stroke the piston passes the port 50, whereupon a pressure impulse is created in the chamber 38 by discharge of motive fluid from the working 60 chamber of the motor through the port 50 into the pipe 47 which communicates through the passages 39 and 40 with said chamber 38. The pressure in chamber 38 upon the valve piston 35 of relatively large area immediately actuates the valve to the position shown in Fig. 2, cutting off admission and establishing exhaust connections. While the descending piston covers the port 50, exhaust from the lower end of the motor cylinder takes place through the chamber 38, the discharge of exhausting fluid from said chamber 65 70 75

being restricted by the small gap 45 through which the chamber is vented and by the packing material 44 through which the exhausting fluid passes. When the descending piston passes below and uncovers the port 50, the exhaust may take place partially through the pipe 47 and port 50 into the motor cylinder space above the motor piston, such exhaust being sufficiently restricted to preserve a pressure of exhausting fluid in the chamber 38. This pressure in chamber 38 will keep the motor valve in the exhaust position so long as the force on the piston 35 exceeds the opposing force on the small valve piston 27. Preferably the device is so designed (as to the ratio of opposing pressure areas of the motor valve and restriction of outlet from the exhaust passages) as to require a substantial load on the jack to impose a sufficient pressure on the exhausting fluid to maintain the motor valve in exhaust position; though the load so required may be only a small proportion of the maximum load sustained by the jack during operation. For example, the motor may be designed so that, when operating with motive fluid at a pressure of about 100 pounds, the valve will be operated from exhaust position to the admission position when the diminishing load on the descending jack falls below about 100 pounds.

In Fig. 1 a load sustained by the jack is diagrammatically indicated at 11. This may represent the weight or partial weight of an automobile body supported by the vehicle springs except to the extent that the weight may be taken by the rocker jack. Let it be assumed, for example, that the vehicle springs support the load in the position shown in Fig. 1, or in other words that the load would be supported by the springs in the position shown at 11 if the rocker jack were removed from under it. Let it be assumed that the rocker jack has been placed under the load while the motor piston is at the bottom of the motor cylinder, and while the valve 24 (Fig. 4) in the motive fluid supply line is closed, and that the jack has been adjusted to leave a clearance of about a half inch or so between the jack head 10 and the load 11. It will be understood that the jack head 10 may be equipped with any suitable saddle bar (not shown) to bear up in lifting engagement with the center bars or with one of the cross bars of the automobile chassis, and that the jack may have been adjusted to leave a clearance between such saddle bar and the part to be lifted. Thus it may be assumed that before starting the motor operation there is a clearance between the jack head 10 and the load 11 (or between a saddle bar on the jack head and the part of the vehicle to be lifted) equal to the distance between the head of the piston bolt 16 and the bottom of the cylinder. Now when the valve 24 (Fig. 4) in the motive fluid supply line is opened, the motor will operate in the manner previously explained, but the first part of the first working or up stroke of the motor piston will be consumed in taking up the aforesaid clearance and bringing the jack head 10 into position for lifting the suspended load 11 with relation to its supporting springs. Continuing its up stroke, the motor piston will lift up the load until the piston passes the cylinder port 50, whereupon the piston will commence to descend and exhaust will take place from the lower end of the cylinder. As the piston descends, the weight of the load 11 is being gradually taken up by the vehicle springs, so that as the piston approaches the position shown in Fig. 75

1 there ceases to be enough load on the piston for imposing on the exhausting motive fluid a sufficient pressure to hold the motor valve in exhaust position; hence the valve will resume 5 position for admitting motive fluid to the lower end of the cylinder. Thus the piston will not descend clear to the bottom of the cylinder, nor quite to the position where it commenced to take up the load on its first up stroke. In short the 10 working stroke of the piston will automatically accommodate itself to the original clearance between the jack head and the load, and will be less than the full possible working stroke by an amount somewhat in excess of the clearance 15 aforesaid; with the desirable results that the jack will not be released from the vehicle body, and the reciprocation of the load will be from a point where a certain load is carried by the piston. It will be understood that if the original clearance 20 between the jack head and the load (or between the saddle bar carried by the jack head and the part of the automobile body or chassis frame to be lifted) should be only a slight clearance, the motor piston would have an accordingly longer 25 working stroke, and if the said clearance should be an inch or more the motor piston would have an accordingly shorter stroke; so that it is easily possible, merely by adjusting the jack to provide more or less clearance between it and the load, to control the stroke of the motor piston, and accordingly to vibrate or move up and down the load with either short or slight up and down movements or longer up and down movements. While the load 11 in Fig. 1 has been assumed to 30 be supported by vehicle springs in the position shown in Fig. 1, it may also be assumed to have been raised from a somewhat lower position by the motor; so that Fig. 1 may be considered either as representing the rocker jack motor in 35 the operation of reciprocating the load carried thereby, or as representing the motor when it first commences to lift the load relative to its support by the vehicle springs.

Cessation of operation of the motor is of course accomplished by closing the valve 24 (Fig. 4) in the motive fluid supply line. If the rocker jack is to be removed from under the motor vehicle, or if it is desired to release the jack from the load, the valve 24 should be closed while the 45 motor piston is descending, the motor controlling valve being in the exhaust position shown in Fig. 2. Upon closing the valve 24, a small amount of motive fluid will be trapped in the inlet passage 23 (Fig. 4) and lower end of the chamber 50 in which the valve piston 27 works. As the piston descends, the small amount of air so trapped will push up the motor valve to the position shown in Fig. 1, whereupon the valve is immediately returned to the exhaust position by the motion of a spring 53 arranged in the chamber 55 38 and acting on piston 35. The motor piston may therefore descend to the bottom of the motor cylinder, allowing release of the jack from the load.

60 It is sometimes desirable to use a rocker jack for the purpose of an ordinary pneumatic lifting jack, as for example where an automobile axle is to be lifted and held raised to permit removal of a tire. This can be accomplished with the 65 illustrative rocker jack by closing the valve 52 (Fig. 5), with the effect of closing the port 50 and therefore preventing operation of the motor controlling valve to position to allow exhaust. Assuming the valve 52 (Fig. 5) to be closed, and the valve 24 (Fig. 4) to be opened when the

piston is at the bottom of the cylinder, the piston with the load above it would simply be raised and held in raised position. This condition would continue until the valve 52 is reopened to cause reverse action of the pressure operated motor controlling valve to position to allow exhaust.

An advantage among others in having exhaust take place through the port 50 into the cylinder space above the piston is that as the piston descends, and as the oil saturated felt ring 19 of the descending piston passes the port 50, the jet of exhausting fluid issuing therefrom will atomize and spray oil against the piston rod, keeping the latter lubricated. Exhaust into the upper chamber of the cylinder also is substantially silent, and exhaust through the port 50 in addition to the exhaust through the chamber 38 is desirable to provide additional exhaust after the weight of the automobile body carried by the motor jack has been largely transferred to the supporting springs of the vehicle. However the invention in its broadest aspect does not depend upon an arrangement providing for an exhaust into the motor cylinder, it being sufficient for the broad purpose of the invention to establish communication between the working chamber of the motor cylinder and the chamber 38 of the valve operating piston 35 as the motor piston completes or is about to complete its working stroke. It is therefore within contemplation to employ, if desired, a spring actuated check valve normally closing the port 50, such valve adapted to open only under pressure of motive fluid in the working chamber of the motor cylinder. Such a valve is shown in 54 in Fig. 6. If such check valve should be employed, the port 50 would open when the motor piston moves above it, but would be closed at all times except when the port or a part of the port is below the lower edge of the packing ring 18 of the piston. In that case the exhaust would take place entirely through the chamber 38 or in part through said chamber and such additional exhaust passage, if any, as might be provided.

The motor piston is to be considered as above the port 50 when it is sufficiently above the lower side of the port to cause a pressure in the chamber 38 for operating the motor valve to position for admission. Inasmuch as the piston of the illustrative motor is equipped with the packing ring 18 depending below the piston head, the said piston of the illustrative motor is to be considered as above said port 50 when the lower edge of the packing ring 18 is sufficiently above the lower side of said port to cause said effective pressure in the chamber 38.

If the motor should be equipped with a type of jack capable of manual operation for load lifting, and if before operation of the motor and while its piston is at the bottom of the cylinder the jack should have been manually operated to lift the automobile body relative to its supporting springs, then of course in the ensuing operation of the motor the piston would always descend to the bottom of the cylinder, after which the pressure in the exhaust passages would of course cease or fall so low as to permit the motor controlling valve to resume position for admission. To release such type of jack from the load, after stopping the operation of the motor, would of course be accomplished by reverse manual operation of the jack to lower it from the suspended load.

Obviously detail changes may be made in the structural features of the parts described with-

out changing the essential character of the motor or departing from the principle of the invention; it being understood that the invention is not limited to the specific embodiment selected for illustration, and that reservation is made of such variations, modifications, and mechanical equivalents of structural parts as fall within the spirit and perview of the claims.

I claim as my invention:

1. In a rocker jack motor of the single acting fluid pressure type comprising an upright motor cylinder and jack-carrying piston working therein, a valve operated by pressure of motive fluid from a source of supply for admitting such fluid to the motor and reversely operable by opposing pressure to cut off admission and to establish exhaust connections, said valve having a relatively small pressure area always exposed during motor operation to said first mentioned pressure and a many times larger opposing pressure area exposed during exhaust to pressure of exhausting fluid, there being a passage through which the cylinder exhausts having a chamber in which said larger area is so exposed, said passage having restricted outlet, and a lateral cylinder port connected with said passage and which the motor piston passes in its working stroke with the effect of creating in said chamber a sudden pressure on said larger area which forces the valve to position for exhaust, the relationship between said areas and restriction of flow of exhausting fluid being such that said pressure of exhausting fluid on said larger area holds the valve in exhaust position while the descending piston sustains a load in excess of a certain value but becomes insufficient for said purpose when said load falls below said value, whereby in using the device for rocking or vibrating an automobile body, under such conditions that the first up stroke of the piston lifts the body from a position in which it was supported entirely or substantially entirely by its springs, the ensuing down stroke will be sufficiently less than said first up stroke to prevent release of the jack from the automobile body.

2. In a rocker jack motor of the single acting fluid pressure type comprising an upright motor cylinder and jack carrying piston working therein, a pressure operated valve for controlling admission and exhaust of motive fluid to and from the motor, said valve having a relatively small pressure area always exposed during motor operation to pressure of the motive fluid to be admitted and having a relatively large opposing pressure area, there being a passage through which the cylinder exhausts from its lower end and a chamber in which pressure acts on said large area in opposition to the pressure on said small area, and a lateral cylinder port which the motor piston passes in its up stroke communicating with said chamber whereby pressure therein to operate the valve to exhaust position is created when the motor piston is above said port, there being restriction of outlet of exhausting fluid to maintain a pressure thereof in said chamber during exhaust whereby to hold the valve in exhaust position, said port affording an additional outlet for exhausting fluid after the piston in its return stroke has passed and uncovered said port, the arrangement being such as to require imposition of at least some load on the jack in order to maintain a sufficient pressure of exhausting fluid on said larger area to hold the valve in exhaust position.

3. In a single acting fluid pressure motor com-

prising a cylinder and piston working therein, a valve operated by pressure of motive fluid from a source of supply for admitting such fluid to the working end of the cylinder, said valve having relatively large and small pressure areas the smaller of which is always exposed during motor operation to said pressure, a vented chamber in which fluid pressure acts on said large area in opposition to the pressure on said small area, a passage in communication with said chamber and with a lateral port in the motor cylinder which is passed by the motor piston in its working stroke, the valve being reversely operable to cut off admission by pressure created in said chamber on said large area in consequence of said passing of said port, and an exhaust passage connecting the working end of the cylinder with said vented chamber while the valve is in its reverse position, the valve being maintained in such reverse position so long as the force on said large area exceeds the opposing force on said small area, the exhaust being through said vented chamber while said port is covered by the motor piston on its return stroke and thereafter partly through said vented chamber and partly through said port and non-working end of the cylinder.

4. In a single acting fluid pressure motor comprising a cylinder and piston working therein, a lateral cylinder port which the motor piston passes in its working stroke, a pressure operated valve for controlling admission and exhaust of motive fluid to and from the working end of the cylinder, said valve comprising a relatively small piston exposed to pressure of motive fluid from a source of supply and operable thereby to position for admission, a relatively large piston by pressure on which the valve is operable to position to cut off admission, there being an exhaust passage connected with the working end of the cylinder when the valve is in position to cut off admission, a vented chamber in which said relatively large piston works, a passage in communication with said chamber and connected with said lateral port of the motor cylinder, whereby pressure for reversely operating the valve is created in said chamber when the motor piston in its working stroke passes said port, said exhaust passage being in communication with said chamber and with said lateral cylinder port, the exhaust taking place through said chamber while the motor piston in its reverse stroke covers said port and thereafter taking place at least in part through said port into the cylinder space above the motor piston and being restricted, and the valve being held in exhaust position so long as the force on said large piston exceeds the opposing force on the small valve piston.

5. In a single acting fluid pressure motor having a lateral cylinder port through which motor exhaust takes place at least in part, a ring of oil-saturated air-permeable material carried on the upper side of the motor piston and which moves across said port, whereby the jet of exhausting fluid can atomize oil from said material and blow it against the piston rod.

6. In a fluid pressure motor, a tubular piston rod and piston secured thereto in the manner described, said rod having an internal annular groove and a locking ring sprung therein and a part retained therein by said ring, and a clamp bolt connecting said part with the piston and thereby clamping the piston rod to the piston.

7. In a single acting fluid pressure motor comprising a cylinder and piston working therein, a valve constantly urged by live fluid pressure to

position for admitting motive fluid to the cylinder and reversely operable by opposing pressure to position for exhaust, there being motive fluid inlet and exhaust passages connected in alternation with the cylinder by operation of said valve, a chamber in constant communication with said exhaust passage in which pressure acts on said valve in opposition to said first mentioned pressure and through a larger area of pressure application than that through which said first mentioned pressure acts, and a lateral cylinder port which the motor piston passes in its working stroke and through which when so passed working fluid is temporarily released, said port communicating with said chamber in which upon such release a sudden pressure is created which forces the valve to position for exhaust, there being no communication between said chamber and the working chamber of the cylinder except temporarily through said port and thereafter through said exhaust passage during the period of exhaust, there being restriction of outlet of exhausting fluid and the pressure thereof holding the valve in exhaust position so long as the force thereby exerted on the valve exceeds the opposing force thereon.

8. In a single acting fluid pressure motor comprising a cylinder and piston working therein, a valve constantly urged by live fluid pressure to position for admitting motive fluid to the cylinder and reversely operable by opposing pressure to position for exhaust, there being motive fluid inlet and exhaust passages connected in alternation with the cylinder by operation of said valve, said exhaust passage having restricted outlet, a chamber in constant communication with said exhaust passage in which pressure acts on said valve in opposition to said first mentioned pressure and through a larger area of pressure application than that through which said first mentioned pressure acts, and a lateral cylinder port which the motor piston passes in its working stroke and through which when so passed working fluid is temporarily released, said port communicating with said chamber in which upon such release a sudden pressure is created which forces the valve to position for exhaust, said cylinder port affording an additional outlet from said exhaust passage after the motor piston in its return stroke has passed and uncovered said port, the valve being held in exhaust position by the pressure of exhausting fluid so long as the force thereby exerted on the valve exceeds the opposing force thereon.

9. In a single acting fluid pressure motor comprising a cylinder and piston working therein, a valve constantly urged by live fluid pressure to position for admitting motive fluid to the cylinder and reversely operable by opposing pressure to position for exhaust, there being motive fluid inlet and exhaust passages connected in alternation with the cylinder by operation of said valve, said exhaust passage having restricted outlet, a chamber in constant communication with said exhaust passage in which pressure acts on said valve in opposition to said first mentioned pressure and through a larger area of pressure application than that through which said first mentioned pressure acts, and a lateral cylinder port which the motor piston passes in both its working stroke and return stroke and through which when passed by the piston in its working stroke the working chamber of the cylinder temporarily communicates with said first mentioned chamber in which is consequently created a sud-

den pressure which forces the valve to position for exhaust, and a check valve normally closing said port and adapted to open only under the pressure of the working fluid in the working chamber of the cylinder, the valve being held in exhaust position by the pressure of exhausting fluid so long as the force thereby exerted on the valve exceeds the opposing force thereon.

10. In a single acting fluid pressure motor comprising a cylinder and piston working therein, a valve constantly urged by live fluid pressure to position for admitting motive fluid to the cylinder and reversely operable by opposing pressure to position for exhaust, there being motive fluid inlet and exhaust passages connected in alternation with the cylinder by operation of said valve, said exhaust passage having restricted outlet, a vented chamber included in said exhaust passage and in which pressure acts on said valve in opposition to said first mentioned pressure and through a larger area of pressure application than that through which said first mentioned pressure acts, and a lateral cylinder port connected with said exhaust passage and which the motor piston passes in its working stroke with the effect of creating in said chamber a sudden pressure which forces the valve to exhaust position, the valve being held in exhaust position so long as the force exerted thereon by pressure in said chamber exceeds the opposing force thereon, the exhaust from the cylinder taking place through said vented chamber while the piston in its return stroke covers said port and thereafter partly through said chamber and partly through said port and the non-working end of the cylinder.

11. In a single acting fluid pressure motor comprising a cylinder and piston working therein, a valve comprising a small piston for controlling admission and exhaust of motive fluid to the cylinder, there being motive fluid inlet and exhaust passages connected in alternation with the cylinder by operation of said small piston, a chamber in communication with said inlet passage in which said small piston works, said small piston being constantly urged by the inlet pressure in said chamber to position for admission, pressure operated means of greater area than the pressure area of said small piston for operating it to position for exhaust, a chamber in which said means works and which is in constant communication with said exhaust passage and connected thereby with the working end of the cylinder when the valve is in exhaust position, the pressure in said second mentioned chamber on said means being in opposition to said first mentioned pressure on the small piston, and a lateral cylinder port connected with said exhaust passage and which the motor piston passes in its working stroke with the effect of creating in said second mentioned chamber a sudden pressure on said means which forces the small piston to position for exhaust, the small piston being held in exhaust position so long as the force on said means exceeds the opposing force on the valve.

12. In a single acting fluid pressure motor

comprising a cylinder and piston working therein, a valve comprising a small piston for controlling admission and exhaust of motive fluid to the cylinder, there being motive fluid inlet and exhaust passages connected in alternation with the cylinder by operation of said valve, a chamber in communication with said inlet passage in which said valve works, the valve being constantly urged by the inlet pressure in said chamber to position for admission, pressure operated means of greater area than the pressure area of said valve for operating it to position for exhaust, a chamber in which said means works and which is in constant communication with said exhaust passage and connected thereby with the working end of the cylinder when the valve is in exhaust position, the pressure in said second mentioned chamber on said means being in opposition to said first mentioned pressure on the valve, and a lateral cylinder port in communication with said second mentioned chamber and which the motor piston passes in its working stroke with the effect of creating in said second mentioned chamber a sudden pressure on said means which forces the valve to position for exhaust, the valve being held in exhaust position so long as the force on said means exceeds the opposing force on the valve, said exhaust passage having restricted outlet and said port affording additional outlet for exhausting fluid after the motor piston in its return stroke has passed and uncovered said port.

13. In a single acting fluid pressure motor comprising a cylinder and piston working therein, a valve comprising a small piston for controlling admission and exhaust of motive fluid to the cylinder, there being motive fluid inlet and exhaust passages connected in alternation with the cylinder by operation of said valve, a chamber in communication with said inlet passage in which said valve works, the valve being constantly urged by the inlet pressure in said chamber to position for admission, pressure operated means of greater area than the pressure area of said valve for operating it to position for exhaust, a vented chamber in which said means works and which is connected by said exhaust passage with the working end of the cylinder when the valve is in exhaust position, the pressure in said vented chamber on said means being in opposition to said first mentioned pressure on the valve, and a lateral cylinder port connected with said exhaust passage and which the motor piston passes in its working stroke with the effect of creating in said vented chamber a sudden pressure on said means which forces the valve to position for exhaust, the valve being held in exhaust position so long as the force on said means exceeds the opposing force on the valve, the cylinder exhausting through said vented chamber while the piston in its reverse stroke covers said port and thereafter exhausting partly through said vented chamber and partly through said port and the non-working end of the cylinder.
